UNITED STATES PATENT OFFICE.

LELAND G. FAIRBANK, OF SAN FRANCISCO, CALIFORNIA.

WAVE MOTOR.

Application filed November 27, 1923 Serial No. 677,299.

The present invention relates to improvements in water motors, and has particular reference to a motor utilizing a continuous flow of water such as occasioned by the tides in the ocean or by the natural flow of a river, for the purpose of producing power. It is particularly proposed to provide a motor of this character that will automatically adjust itself to the direction of the flow, so that the change of the tides will not in any way interfere with the proper operation of the motor.

It is further proposed to construct propelling means forming part of my motor in such a manner that the proper position of the propeller relative to the direction of flow is continuously maintained so that when the direction of flow is changed slightly the propeller will automatically follow the change and assume a position in which the flow of water can operate on the propeller to the best advantage.

It is further proposed to provide in connection with my water motor suitable means for transferring power from a rotary shaft to an electric generator or similar device adapted to convert mechanical power created by the flow of water into electrical power. It is further proposed to provide suitable means for raising and lowering the propeller portion of my water motor and to provide further means in conjunction therewith allowing the raising and lowering means to be actuated by the propeller. Further objects and advantages of my device will appear as the specification proceeds.

The preferred form of my invention is illustrated in the accompanying drawings, in which Figure 1 shows a side view of my water motor; Figure 2 a sectional view taken along line II—II of Figure 1; Figure 3 an enlarged longitudinal section through a portion of my device; Figure 4 an end view of one propeller; Figure 5 a side view of a portion of the same; Figure 6 an enlarged detail view illustrating the means for securing a propeller blade to a hub; Figure 7 a section taken along line VII—VII of Figure 6; Figures 8 and 9 detail views of a member limiting the swinging motion of a blade on the propeller; and Figure 10 an enlarged detail view of the central portion of Figure 3. While I have shown only the preferred form of my invention, I wish to have it understood that various changes or

modifications may be made within the scope of the claims hereto attached without departing from the spirit of the invention.

The supporting structure of my water motor comprises a frame (1) of any suitable construction adapted to rest on the beams (2) which latter are supported on two piers (3) disposed at a distance from one another. The frame (1) preferably comprises the transverse members (4) which may be made of channel iron, and the longitudinal members (6) made of any suitable cross-section. Plates (7) are supported on the frame and allow a second frame (8) of any suitable construction to ride thereon by means of the wheels (9). The latter frame has a cup-shaped member (11) centrally depending therefrom, and a registering cup-shaped member (12) is adapted to receive the member (11) with freedom of rotary motion, with a retaining ring (13) holding the two cups in engagement. It will thus be seen that the frame (8) is adapted to revolve on the central axis of the whole device, which latter central axis is represented by the vertical shaft (14).

The propeller of my device is suspended from the revolving frame (8) in the following manner, as particularly well illustrated in Figure 3. Two bearings (16) are supported by means of brackets (17) between transverse members (18) and have rotatably mounted therein sleeves (19) provided at their upper ends with bevel gears (21) and threaded interiorly to receive the threaded rods (22) rising from a third frame (23). It is apparent that when the bevel gears (21) are rotated either by hand or by power means, to be described hereinafter, the third frame (23) will be raised or lowered according to the direction of rotation of the bevel gears (21). Suitable guide means for the frame (23), which latter supports the propeller arrangement, are provided in the heavy columns (24) rising from the latter frame and slidably extending through bearings (26) provided in the frame (8) and in the superstructure (9') secured on said frame.

The bevel gears (21) are actuated by means of pinions (27) on radial shafts (28) which latter terminate at their inner ends in pinions (29) meshing with two bevel gears (31) mounted on the vertical shaft (14) with freedom of rotary motion. A sleeve (32)

slidable on the shaft (14) is provided with lugs (33) on its end faces, which latter are adapted to engage with recesses (34) in the faces of the upper or lower bevel gear (31) 5 when the sleeve is pushed upwardly or downwardly by means of the forked lever (36) engaging the grooved circumferential face of the sleeve (32). It will thus be seen that when the shaft (14) is rotated by means of 10 the propeller, to be described hereinafter, either the upper or the lower bevel gear (31) may be engaged with the pinions (29) for imparting rotary motion to the bevel gear (21) for raising or lowering the propeller 15 arrangement, and that the direction of motion of the latter is governed by the selection between the two bevel gears (31). The shafts (28) may also be turned by hand by means of a lever (30) engaging the collar 20 (35) as shown in Figure 3.

The lower frame (23) supports on suitable bracing members (37) and (38) a horizontal shaft (39) on which are mounted a plurality of propellers (41). A housing 25 (42) surrounding the central portion of the shaft protects a bevel gear (43) keyed to the shaft and meshing with a pinion (44) disposed on the lower end of the vertical shaft (14) so that the shaft (39) rotates the 30 vertical shaft (14) when the propellers are working. The ends of the horizontal shaft (39) have angle irons (46) extending therefrom, which latter angle irons support the rudder (47) extending through the full 35 length of the water motor and serving as a stabilizer for the same.

One of the propellers is illustrated in detail in Figure 4 in connection with Figures 40 5 and 6, from which it appears that a plurality of spokes (48) are rotatably supported in a hub structure (49) fixed to the shaft (39) and a peripheral ring (51). Each spoke has a suitable blade (52) secured thereto by means of lugs (53) so that 45 each blade swings freely on the axis of its respective spoke. This swinging motion is, however, limited by means of the confining members (54) secured to arms (56) extending from a sleeve (57) rotatable on the spoke (48) and disposed at an angle to the plane of the spokes, as shown in Figure 5. In end view the members (54) are curved, as shown in Figure 8, and also in the main view of Figure 4. The arms (56) which 50 run parallel to the shaft (39) are sufficiently long to accommodate the free ends of the confining members (54) of the preceding spoke, as shown in Figure 5. It will be seen that due to this construction each blade 55 can play within the limits of the confining members but is prevented from going beyond a pitch previously decided upon. Further means for limiting the play of the blades are provided in the lugs (58) secured on the spokes near the hub and suit-

able stops (59) provided on the hub, which latter two enter into engagement at the same time that the blade strikes the confining member (54). Thus each propeller is constructed to respond to the flow of water, 70 no matter in what direction the water flows, and each propeller blade can readily adjust itself to a reversal in the flow of water such as would occur when the tides change.

The frame (8) has a platform secured 75 thereon, which latter supports the electric generators (62) disposed on opposite sides of the vertical shaft (14). A bevel gear (63) 80 slidable on the shaft (14) but partaking of its rotary motion, engages with the bevel pinions (64) mounted on the shafts (66) of the generators. Suitable change speed arrangement (67) may be introduced into the generator shafts for transmitting power at 85 desired speeds.

The operation of the whole device should be readily understood from the foregoing description. The frame (8) which is supported on the frame (1) like a turn-table, 90 has the propeller arrangement suspended therefrom by means of the rods (22), which latter may be raised or lowered through the bevel gear arrangement shown in Figure 3, while the columns (24) serve as guides for the propeller arrangement. Power is transmitted to the two generators from the horizontal shaft (39) through the vertical shaft (14) occupying the center of the whole arrangement. The propellers themselves tend to keep the shaft (39) in the direction of 95 the flow, and remain operative no matter what direction the water comes from since the blades swing around on a reversal of the flow of the water. The rudder or stabilizer (47) tends to hold the whole propeller 100 arrangement in an operative position and allows the same to operate under the most favorable conditions.

I claim:

1. In a water motor, a supporting structure, a rudder plate depending therefrom with freedom of rotary motion, a driving element associated with the plate, flow responsive means thereon for imparting motion to the same, means for raising and lowering the rudder plate, and an operative connection between the latter means and the driving element allowing the latter to operate the former.

2. In a water motor, a stationary frame, a turntable revolvable thereon, an elongated centrally recessed rudder plate suspended from the turntable, a shaft arranged longitudinally in the recess of the plate and propeller blades mounted on the shaft for imparting rotary motion to the shaft.

3. In a water motor, a stationary frame, a turntable revolvable thereon, a rudder plate suspended from the turntable, a shaft supported in a plane substantially parallel with

the rudder plate and propeller blades mounted on the shaft for imparting rotary motion to the shaft.

4. In a water motor, a stationary frame, a turntable revolvable thereon, a rudder plate, vertical rods supporting the rudder plate extending through the turntable, threaded means associated with the turntable for lowering and raising the rods, a horizontal shaft supported on the plate, propeller blades on the shaft for imparting rotary motion to the shaft and an operative connection between the shaft and the threaded means allowing the former to operate the latter for raising and lowering the rudder plate.
5. In a water motor, a stationary frame,

a turntable revolvable thereon, a rudder plate, vertical rods supporting the rudder plate extending through the turntable, threaded means associated with the turntable for lowering and raising the rods, a horizontal shaft supported on the plate, propeller blades on the shaft for imparting rotary motion to the shaft and an operative connection between the shaft and the threaded means allowing the former to operate the latter for raising and lowering the rudder plate.

LELAND G. FAIRBANK.
